UNITED STATES PATENT OFFICE.

EDWIN S. MIX, OF ROCHESTER, NEW YORK.

LAUNDRY MARKER.

1,409,391.

Specification of Letters Patent. Patented Mar. 14, 1922.

Application filed April 1, 1920. Serial No. 370,529.

To all whom it may concern:

Be it known that I, EDWIN S. MIX, a citizen of the United States, residing at Rochester, in the county of Monroe and State of New York, have invented certain new and useful Improvements in Laundry Markers; and I do hereby declare the following to be a full, clear, and exact description of the invention, such as will enable others skilled 5 in the art to which it appertains to make and use the same.

This invention relates to a device for marking articles of clothing temporarily in a public laundry.

15 For the purpose in question it is common to use a safety-pin of ordinary form, to which a sheet-metal tag or label is attached, this tag having a number by which the article of clothing is identified.

20 It has been found that a safety-pin so used is frequently detached from the article to which it has been applied, during the operation of the laundry machinery, which results in great inconvenience and loss; and 25 the object of the present invention is to produce a simple and inexpensive marker, of the type in question, in which such accidental detachment of the pin will be prevented.

30 To the foregoing end it is proposed, in accordance with the present invention to use a sliding locking device, cooperable with the two limbs of the pin in such a manner as to lock them adjustably against the relative 35 movement.

The invention is more fully described in connection with the accompanying drawings showing the preferred form thereof. In these drawings, Fig. 1 is a side-elevation, 40 from the rear, of a marker embodying the invention; Fig. 2 is a section on the line 2-2 in Fig. 1; and Fig. 3 is a front-elevation of the tag and adjacent parts of the pin.

45 In the drawings the invention is illustrated as embodied in a marker comprising a safety-pin 5, having the usual general form of such devices, and provided with the usual shield 6 and point 7 on its two ends.

50 The locking-device is in the form of a sheet-metal plate 8, which is arranged to embrace and slide upon the two limbs of the pin. For this purpose the plate is provided with two parallel rearwardly bent marginal 55 flanges 9, which are perforated with elongated holes, as shown in Fig. 2, to receive

the limbs of the pin. The pin differs from the ordinary form in the respect that one of its limbs is provided with one or more recesses 10, these recesses being formed, in 60 the illustrated pin, by bending a portion of the wire to a sinuous form.

When the pin is used the plate 8 is first slid toward the bent portion of the pin, and the pin is then attached to the article in the 65 usual manner. The plate is then slid towards the head of the pin as far as is permitted by the bulk of the material penetrated by the pin, thus bringing it into engagement with one or the other of the recesses 10. Owing to the resiliency of the wire of which the pin is formed the recesses tend to prevent sliding movement of the plate, which is thus retained in the position to which it has been moved, and the 70 plate in turn locks the pointed end of the pin against the movement by which it may be disengaged from the shield. The locking function is reinforced also by the bulk of the material which is confined between the 75 limbs of the pin adjacent to the shield.

The locking plate 8 is preferably, though not necessarily, employed also as a tag, being stamped or otherwise marked with a 80 number as shown in Fig. 3.

The invention is not limited to the embodiment thereof hereinbefore described and shown in the accompanying drawings, but it may be embodied in various other forms within the scope of the following claims. 85

The invention claimed is:

1. A laundry-marker comprising: a safety-pin provided with a recess on the inner side of one of its limbs; and a locking-device 90 slideable on both limbs of the pin and having surfaces engaging the inner sides thereof, the limbs of the pin pressing resiliently against said surfaces when the pin is in closed position and the locking-device in engagement with said recess, whereby the locking device is yieldingly retained against sliding movement and in turn tends to prevent movement of the limbs of the pin towards each other. 100

2. A laundry-marker comprising: a safety-pin provided with a sinuously-bent portion in one of its limbs; and a locking device having opposite marginal portions embracing and slideable upon both limbs of the pin. 105

3. A laundry-marker comprising: a safety-pin provided with a sinuously-bent portion in one of its limbs; and a sheet-metal mem- 110

ber having two opposite marginal flanges which are perforated to receive, and slide upon, both limbs of the pin.

4. The combination of a safety-pin and a locking-device slidable on and connecting the limbs of the pin; the pin and the locking device being provided with interengaging means for retaining the latter, against

sliding movement, in either of a plurality of positions at varying distances from the head of the pin, and the locking-device being adapted, in each of such positions, to restrain movement of the limbs of the pin towards each other.

EDWIN S. MIX.
